SAFETY HOLDER FOR INSTRUMENTS

William H. Fraser, Reno, Nev.

Application April 23, 1946, Serial No. 664,188

1 Claim. (Cl. 2—249)

1

The present invention relates to improvements in a safety holder for an instrument, and it consists of the combinations, constructions and arrangement of parts hereinafter described and claimed.

An object of my invention is to provide a safety holder, which is designed to hold pens, pencils or other instruments in a garment pocket and is made to prevent these instruments from accidentally dropping out of the pocket.

More specifically described, I propose to fasten a holder at the entrance to a garment pocket. This holder is arranged to have the usual spring clip of a pen, pencil, or other like instrument engaged therewith. The holder engages with the clip and prevents accidental withdrawal of the instrument. However, my holder is so constructed that it will release the instrument for withdrawal when the latter is moved into a predetermined position relative to the holder.

Other objects and advantages will appear as the specification continues, and the novel features of my invention will be set forth in the claim hereunto appended.

For a better understanding of my invention, reference should be had to the accompanying drawing, forming part of this application, in which:

Figure 1 is a front elevation of a garment pocket, disclosing my safety holder applied thereto with a pen and pencil set anchored to the holder;

Figure 2 is a transverse section taken through the holder and showing a pen cap secured thereto;

Figure 3 is a view similar to Figure 2, but illustrating the cap rocked into a position to free the spring clip from the holder;

Figure 4 is an isometric view of the holder;

Figure 5 is a front elevation of a modified form of my safety holder as applied to a garment pocket; and

Figure 6 is a transverse section through Figure 5.

While I have shown only the preferred forms of my invention, it should be understood that various changes, or modifications, may be made within the scope of my annexed claim without departing from the spirit thereof.

Referring now to the form of my invention as shown in Figures 1 to 4, inclusive, it will be noted that I have provided a safety holder indicated generally at A. This holder is a spring clamp-like structure that is adapted to be secured over the marginal portion I of the entrance to a gar-

2

ment pocket B. The holder includes rear and front plates 2 and 3, respectively, which are interconnected by a rounded portion 4 extending lengthwise of the holder.

5 In Figures 1 to 3, inclusive, I have shown a plurality of prongs 5 that are struck out of the rear plate 2. These prongs are arranged to allow the holder A to be slipped over the marginal portion I of the garment pocket, but engage with 10 the garment to prevent the holder from slipping off of the garment.

The holder A is further provided with a flange 6 extending lengthwise of the front plate 3 and projecting forwardly therefrom at a downwardly-extending angle relative thereto. In Figure 1, I disclose a pen C and pencil D, which have been inserted into the garment pocket B. These writing instruments are provided with the usual spring clips 1. Each clip is fashioned with an 15 inturned portion or bead 7a at its free end, which engages below the flange 6 when the instrument is inserted into the pocket and the spring clip moved downwardly over the front plate 3. The inclination of the flange 6 aids in allowing the 20 inturned portion or bead 7a to be pushed over the flange.

In order to remove the pen C or pencil D from the pocket B, these instruments are rocked into a slightly inclined position, as suggested by the 25 pen cap in Figure 3. During this movement, the rounded portion 4 serves as a fulcrum against which the spring clip 7 bears. The inturned portion or bead 7a is forced away from the writing instrument sufficiently to disengage it from the outwardly-extending flange 6. The position of 30 the writing instrument with respect to the holder A at this time is illustrated in Figure 3, and the instrument may be withdrawn from the pocket.

It will be noted that the holder A actually 35 forms a protector over the marginal portion I of the garment pocket, thus preventing fraying of the latter due to insertion and withdrawal of the instrument. The pocket B may be in a vest, shirt or any other suitable garment.

40 Turning now to the modification, as disclosed in Figures 5 and 6, I have shown the cap of the pen C inserted into the pocket B. The safety holder in these views is designated by the reference letter E. The holder includes a plate 8 that is placed against the outer surface of the marginal portion I of the garment pocket. This plate has a pair of spring-pressed clamps 9 hinged thereto, as at 10. These clamps engage with the inner surface of the pocket, and are formed with prongs 11 that project toward the 45 plate 8 and engage with the cloth of the pocket.

Springs 12 are accommodated within the housings 13 defined by the hinges 10, as shown in Figure 5. The ends 12a of the springs bear against the plate 8, while the spring ends 12b engage with the clamps 9. The springs are coiled in such a manner as to yieldingly urge the clamps 9 toward the plate 8 and anchor the holder E to the marginal portion f of the pocket.

The plate 8 further is provided with an outwardly and downwardly-inclined flange 14 along its bottom. This flange engages above the in-turned portion or bead 7a on the spring clip 7, and serves to retain the instrument in the garment pocket. Plate 8 may be fashioned with a reinforcing rib 15. The latter also acts as a fulcrum about which the writing instrument may be rocked for freeing the in-turned end or bead 7a from the flange 14. The downward inclination of the flange 14 facilitates the introduction of the bead 7a over the flange.

The hinge housings 13 are sufficiently large to abut against the clip 7 when the writing instrument is moved laterally along the plate 8. Thus the instrument is prevented from sliding over the ends of the holder E.

Although I have illustrated and described a pen and pencil set, I desire to point out that many other instruments are provided with spring clips for holding them in garment pockets. These include engineer's scales, tire pressure gauges, pen-shaped flashlights and thermometers. The generic term "instruments" will be used accordingly in the attached claim.

I claim:

In a safety holder for securing an instrument in a garment pocket; a clamp-like member U-shaped in vertical cross section and having an inner plate portion for entering the pocket interior and an outer plate portion of approximately the same size as the inner one for extending over the front of the outer surface of the pocket; said clamp-like member frictionally gripping the front wall of the pocket and having its outer plate portion fashioned with a flange that projects outwardly therefrom; the flange being positioned to

engage above an inturned portion disposed at the free end of the instrument clip when the instrument is inserted into the pocket; the flange preventing the accidental withdrawal of the instrument from the pocket; the clamp-like member having an enlarged semi-cylindrical portion interconnecting the inner and outer plate portions; the plate portions being flat and paralleling one another and being spaced closer together than the diameter of the semi-cylindrical portion; the semi-cylindrical portion serving as a fulcrum about which the instrument clip may be rocked and the lower edge of the inner plate portion serving as another fulcrum about which the instrument may be rocked; the instrument and clip when rocked about their respective fulcrums, moving the inturned end of the instrument clip away from the body of the instrument, thereby causing the inturned end of the clip to become disengaged from the flange and thus permit the ready removal of the instrument from the holder and pocket.

WILLIAM H. FRASER.
